UNITED STATES PATENT OFFICE.

ALBIN WARTH, OF STAPLETON, NEW YORK.

ROTARY PUMP.

SPECIFICATION forming part of Letters Patent No. 297,478, dated April 22, 1884.

Application filed July 26, 1883. (No model.)

To all whom it may concern:

Be it known that I, ALBIN WARTH, of Stapleton, in the county of Richmond and State of New York, have made an invention of certain 5 new and useful Improvements in Rotary Pumps, which are applicable also to rotary engines; and I do hereby declare that the following, in connection with the accompanying drawings, is a full, clear, and exact description and specification of the same.

This invention relates to improvements in that class of rotary pumps or engines in which an oscillating valve is combined with a rotary piston and a cam which operates the valve.

15 The invention consists in the novel combination of devices hereinafter described and claimed, reference being had to the accompanying drawings, in which—

Figure 1 represents a side view, partly in 20 section. Fig. 2 is a transverse section in the plane *xx*, Fig. 1. Fig. 3 is an end view. Figs. 4, 5, 6, 7, and 8 show different positions of the valve, the piston-wheel, and the valve-gear.

Similar letters indicate corresponding parts. 25 In the following description I shall describe my apparatus when used as a rotary pump; but it should be understood that my apparatus can also be used with advantage as a rotary engine driven by steam, compressed air, or any 30 other medium suitable for the purpose.

In the accompanying drawings, the letter *A* designates the cylinder, the heads *B B* of which are provided with openings and stuffing-boxes, through which extends the shaft *C*. This 35 shaft has its bearings in pillow-blocks *D D*, situated at the opposite ends of the cylinder, and in the interior of the cylinder is situated the piston-wheel *E*, which is firmly mounted on the shaft *C*. Said piston-wheel extends 40 throughout the entire length of the cylinder, and it is provided with a projection or rib, *a*, which I denominate the "piston," the outer surface of which is a cylindrical curve of the same diameter, or nearly so, as the bore of the 45 cylinder, so that when the piston-wheel revolves, the outer surface of the piston works in close contact with the inner surface of the cylinder. The shaft *C* is fitted with a belt-pulley, *Q*, to which a belt is applied for the 50 purpose of driving the piston-wheel and causing it to rotate, preferably, in the direction of

the arrow applied to the piston-wheel in Fig. 2; but any other suitable means may be used for the same purpose. The cylinder communicates through an opening, *b*, with the valve-chamber *F*. In the example shown in the drawings the valve-chamber and the cylinder are formed in one and the same piece, and the heads *B B* are common to both. The opening *b* extends from one head of the cylinder to the other, and the valve-chamber communicates through an opening, *c*, with the supply-pipe *G*, and through an opening, *d*, with the discharge-pipe *H*; but, if desired, the valve-chamber, with its outlets *c d*, may be formed 55 separately from the cylinder, and may be secured to the cylinder by proper means; or, if desired, the cylinder as well as the valve-chamber may be made of boiler-iron or other suitable material. From the discharge-pipe 60 *H* extends a channel, *I*, to an opening, *J*, to which an air-chamber or a pressure-gage may be applied. The valve-chamber has a cylindrical bore, into which is fitted the valve *K*, which is mounted on a rock-shaft, *L*, which 65 has its bearings in the pillow-blocks *D D*, Fig. 1. The valve is provided with two wings, *e f*, the outer surfaces of which are turned off, so as to fit the inner surface of the bore of the valve-chamber, and the said valve is so operated that 70 during a large part of the revolution of the piston-wheel one of said wings is in contact, or nearly so, with the cylindrical surface of 75 said piston-wheel, as shown in Fig. 2. This valve thus also acts as an abutment to the piston-wheel, and I will therefore designate it as an "abutment-valve." As both wings of the abutment-valve are subjected to equal pressure, and they are at opposite sides of the valve-shaft, the pressure against one wing is 80 balanced by the pressure against the other, and consequently the abutment-valve can be 85 oscillated freely.

The abutment-valve *K* is combined with the piston-wheel *E* by means which impart to the 90 said valve an oscillating motion, so that the valve-wing *e* is moved out of the way of the piston *a* when the latter is passing the valve *K*, and at the same time the other valve-wing, *f*, is 95 moved to close the opening or port *c*. The 100 means which I use for this purpose, and which I have represented in the drawings, consist of

a cam, M, which is mounted outside of the cylinder on the end of the shaft C, Figs. 1 and 3, and which acts upon a lever, N. This lever has its fulcrum on a stud, *g*, secured in the end of the bed-plate of the pump, and its upper end connects by a link, O, with an arm, P, which is mounted on the end of the rock-shaft L, Figs. 1 and 3.

In the example shown in the drawings the operating-surface of the cam M is made in the form of a cam-groove, and on the lever N is secured a roller-stud, *h*, which engages with said cam-groove. A simple peripheral cam may, however, be used, in which case the roller-stud *h* is held in contact with the surface of the cam by a spring, *i*. If the shaft C revolves in the direction of arrow 1, Figs. 2 to 7, water is drawn in through the pipe G and the water in front of the piston *a* is driven out through the pipe H. The cam M is made preferably of such form that the abutment-valve remains stationary until the piston *a* has reached the position shown in Fig. 8; but when the piston reaches this position the abutment-valve begins to move until it reaches a position slightly beyond that shown in Fig. 6, so as to allow the piston to pass beneath it, when it gradually returns until it again assumes the position shown in Figs. 2 and 8. The acting-surface of the valve-cam M and the curvature of the periphery of the piston are preferably such that during the entire motion of the abutment-valve the surface of the wing *e* remains in contact, or nearly so, with the piston-wheel or with the piston, the valve immediately beginning to move backward or return when the piston has cleared the opening *b*, as shown in Fig. 6, so that there is no free communication at any time between the supply-pipe G and the discharge-pipe H. If the motion of the shaft C be reversed, no change takes place, ex-

cept that the water is drawn in through the pipe H and discharged through the pipe G. If steam or compressed air is admitted through the pipe G, the piston-wheel is caused to revolve in the direction of arrow 1, and the opening *d* forms the exhaust-port. 45

I am aware that it is not broadly new to combine an oscillating valve with a piston-wheel and operating-cam, and such, therefore, 50 I do not claim.

What I claim as new, and desire to secure by Letters Patent, is—

1. The combination of the cylinder, the piston-wheel and piston fitted to revolve within 55 the cylinder, the cylindrical valve-chamber communicating with the cylinder and with the supply and discharge pipes, the oscillating abutment-valve balanced within the valve-chamber, and the cam at the outside of the 60 cylinder for oscillating the valve, substantially as described.

2. The combination of the cylinder, the piston-wheel and piston fitted to revolve within 65 the cylinder, the cylindrical valve-chamber communicating with the cylinder and having the opposite supply and discharge ports, the oscillating abutment-valve arranged in the valve-chamber and composed of the oppositely-projecting wings, said valve being balanced in 70 the valve-chamber by the pressure against one wing being balanced by the pressure against the other wing, and the cam outside of the cylinder, by which motion is imparted to the abutment-valve, substantially as described. 75

In testimony whereof I have hereunto set my hand and seal in the presence of two subscribing witnesses.

ALBIN WARTH. [L. S.]
